UNITED STATES PATENT OFFICE.

H. RAM B. CANNON, OF SARNIA, ONTARIO, CANADA, ASSIGNOR TO THE CARBORUNDUM COMPANY, OF NIAGARA FALLS, NEW YORK, A CORPORATION OF PENNSYLVANIA.

FURNACE.

Application filed February 28, 1921. Serial No. 448,337.

This invention relates to furnaces and to combustion chambers for furnaces and the like. The general object of the invention is to provide a novel and efficient furnace and chamber as well as a chamber which is particularly well adapted for the efficient combustion of pulverized fuel as well as for the heating of various objects by radiation.

In the drawing, my invention is shown as adapted to and employed for the heating of a steam boiler; but it will be understood that, except in so far as the cooperating details are covered in the claims, the invention is not to be limited to such adaptation and use.

In said drawings, Fig. 1 represents a longitudinal sectional elevation of a steam boiler and furnace embodying my invention; Fig. 2 a sectional front elevation, and Figs. 3 and 4 are details in cross section through one of the combustion chambers and taken respectively at approximately the places indicated by the lines 3—3 and 4—4 on Fig. 1.

Describing the various parts by reference characters, 1 denotes the boiler setting generally, the same being made of ordinary fire brick with an inner layer of silica brick or other heat-resisting brick or material. The floor of the setting slopes downwardly and rearwardly from the front, as indicated at 2, and the said setting is provided with an opening 3 therethrough at the bottom of a trough-like depression, for a purpose to be described hereinafter.

Above the boiler setting is a boiler 4, which may be of any standard type, the one shown herein being of the water-tube type.

Within the chamber provided in the setting and between the floor 2 and the boiler, there are mounted a number of my units suitable for efficiently heating the said boiler. Each unit comprises a combustion chamber 5 formed of a plurality of sections each composed of slabs of carborundum, this material being used because of its highly refractory nature, its permeability to heat, and its great capacity for radiation of heat. Each combustion chamber is shown as trapezoidal in section and comprises a plurality of sections each having side pieces 6, each provided with an inwardly projecting ledge or shoulder 7; a cover piece 8; and a bottom piece 9. The top and bottom pieces or slabs and the side pieces or slabs are provided with interfitting

joints, as indicated at 10 and similar joints are provided between the sections themselves. If desired, cement of like material as the slabs may be employed at these joints. The front of each combustion chamber 5 is closed by a plate or slab 11 having an inwardly projecting ledge 12. The rear will be closed by a specially shaped section 13 forming a concaved back for the chamber, for a purpose to be explained hereinafter.

The ledges 7 and 12 support a partition which extends from the front of the chamber toward, but terminates in front of, the rear. The partition comprises a plurality of sections 14, preferably of silicon carbide. The ledges are so arranged that the front of the partition will be supported below the center of the chamber while the rear of the partition is preferably nearly coincident with but slightly below such center, the said partition providing a lower passage, the cross-sectional area of which increases from the front; also an upper passage the cross-sectional area of which increases from the rear toward the front, the said upper and lower passages communicating through the space provided adjacent to the rear wall 13 and around the rear end of the partition.

Toward its rear, the combustion chamber is shaped to conform to the trough-like depression in the floor 2, and each of these combustion chambers is provided with a supporting slab 15 resting on the floor 2, the said slab being of refractory material other than silicon carbide, and provided with projections 15^a adapted to engage the exterior of the combustion chamber and having air circulating spaces 16 between the said projections.

It will be noted that the bottom wall of the combustion chamber slopes downwardly from the front to the rear, being provided with a trough-like depression 17 supported by the like depression in the upper surface of the slab 15. The bottom of this depression 17 is provided with an outlet pipe 18, preferably of carborundum, mounted within the opening 3 and adapted to discharge into a sealed ash pit 19. The bottom of the delivery pipe 18 is provided with a damper 20 by means of which it may be closed at times when it is desired to remove the ashes and slag from the pit 19, whereby the efficient operation of the combustion chamber may

not be interrupted. It will be understood that each combustion chamber 5 will be provided with its own ash pit, whereby the removal of ashes and slag from any one pit 5 will not interfere with the operation of any other combustion chamber. Silicon carbide is the material preferably employed for the combustion chamber because of its refractory nature and its high thermal conductivity, 10 such conductivity being in excess of 0.006 cal/cm²/sec/°C. Other refractory materials having a thermal conductivity in excess of that just mentioned are fused aluminum oxide (Al₂O₃) and fused magnesium oxide (MgO). 15 The combustion chambers thus far described are capable of general use and particularly for use with pulverized fuel. For the purpose of heating efficiently the particular type of boiler 4 shown herein, the upper 20 wall of each chamber is placed in close proximity to said boiler. This enables the combustion chambers to heat the boiler in a most efficient manner by radiation and convection, but mainly by radiation. However, it 25 is desirable in many cases to heat the boilers additionally and directly by convection from the products of combustion. For this purpose, each combustion chamber is provided in its top wall and near the front thereof 30 with ports 21 which permit the gaseous products of combustion to be delivered in operative relation to the front of the boiler. It will be understood that these gaseous products will be directed in any approved manner 35 to the water tubes of such boiler.

It will be noted that the combustion chambers are arranged, not only side by side, but with their sides 6 converging upwardly, whereby the sides of each combustion chamber converge from the bottom toward the top thereof, providing upwardly flaring spaces therebetween. This enables heat radiated at right angles from a wall of one combustion chamber to be reflected in a most efficient 45 manner from the wall of an adjacent combustion chamber (or other object) resulting in greater efficiency than can be obtained where the walls of adjacent chambers are parallel or where the spaces between adjacent chambers taper upwardly. 50

The combustion chambers are arranged to cooperate most efficiently with a boiler of the type shown in Fig. 1, wherein the tubes 4^a extend rearwardly and downwardly from the front header 4^b to the rear header 4^c. For the purpose of utilizing the products of combustion in a most efficient manner, a baffle 4^d extends transversely of the tubes 4^a and is located rearwardly of the header 4^b in such 55 position as to permit the products to be delivered into the flue or space thus formed, as well as to enable the tubes to be heated by the part of the combustion chamber therebelow. These products of combustion pass 60 above the baffle 4^d and are directed down- 65

wardly, by means of baffles 4^e and 4^f, passing beneath the last mentioned baffle and thence upwardly to the stack uptake 4^g.

The combustion chambers as described herein, while capable of use with other fuels, 70 are particularly adapted for the efficient combustion of pulverized fuel. Such fuel will be delivered to the various combustion chambers by means of any standard pulverizing and conveying mechanism, each combustion chamber being shown as provided with a burner 22, through which the mixture of pulverized fuel and air will be admitted to the respective chambers. This mixture is ignited and, before the burning mixture shall have reached 80 the outlets 21, the carbon content will have been completely consumed, delivering gases only through said outlets and to the tubes of the boiler. In its passage through the combustion chamber, some ash and clinker or 85 slag will be produced, the amount depending upon the impurities present in the coal or coke. The combustion chamber becomes intensely heated and the temperature of its walls, in conjunction with the downwardly 90 sloping bottom, the downward slope of the partition 14 and the construction of the rear end of the chamber, causes all such clinker or slag to be delivered in a molten condition by gravity through the pipe 18 and into the ash 95 pit, without accumulating within or adhering in any considerable depth to the inner walls of the combustion chamber and hence without injuring the latter and without the formation of such accumulations as would require 100 the opening up or taking down of the combustion chambers from time to time.

Furthermore, the shape of the rear end of the chamber not only facilitates the discharge 105 of such slag or clinker, but imparts a whirling movement to the gases and particles undergoing combustion, and thus separates a large proportion of the ash that may result from the combustion of the coal, coke, or similar material, depositing the ash within the 110 pit 19.

By the construction described, I have produced, within a given length of furnace, a combustion chamber of such length as to insure the complete consumption of the solid 115 carbon particles as well as the complete combustion of the resultant gases before the latter reach the openings 21. As a result, there is no accumulation of carbon upon the boiler tubes and, for reasons pointed out hereinbefore, there can be no accumulation of slag or clinker upon the same.

The inclination of the combustion chambers not only secures the advantages pointed out hereinbefore but, where these chambers 125 are made up of various sections, with the rear ends supported solidly against the boiler setting, as indicated, the various sections are retained in operative relation to each other 130 by gravity.

Reference has been made heretofore to the progressive increase in cross sectional area of the combustion space within each of the chambers 5. This progressive increase tends to maintain substantially constant the velocity of the fuel elements and gases in their progress through the combustion chamber; as the gases expand, this expansion is taken care of by this increasing cross sectional area, and the combustion is facilitated by this arrangement. This substantially constant speed of the gases contributes to the effective heating of the combustion chamber and consequently to its efficient radiating qualities.

In order to permit the combustion chamber to radiate heat uniformly throughout its extent, the thickness of the walls thereof diminishes from the front or fuel supplying end toward the rear. This will be evident from an inspection of Figs. 3 and 4; the former of which is a sectional view through the combustion chamber near the front end thereof and the latter of which is a similar view taken near the rear end of the said chamber.

In order to utilize to the best advantage the heat-radiating and heat-conveying qualities of my combustion chambers, the top wall of each such chamber is substantially continuous throughout its length, the ports 21 being only of such aggregate area as will permit the products of combustion to pass between the boiler tubes without the development of back pressure.

In addition, the combustion chambers are laterally spaced, as shown in Fig. 2, whereby the sides operate to heat by radiation and convection. Furthermore, the tops of the combustion chambers are arranged in close proximity to and parallel with the inclined tubes of the boiler. This results in a maximum efficiency of the carborundum chambers in heating the boiler tubes by radiation and convection.

By locating the exhaust outlets 21 at the front of the upper combustion passage, the flame may be caused to travel the full length of both combustion passages, with the top of the flame at such outlet or outlets. This insures combustion throughout the entire effective length of the combustion chamber, including the two passages. As a result, the combustion chamber will be uniformly heated throughout its extent, enabling it to operate with the maximum efficiency. The combustible mixture within and throughout the length of the upper passage will be heated by the lower passage and the partition 14, facilitating the quick and complete combustion of the mixture in the upper passage.

As a result of this construction of combustion chamber, the latter can be heated to a higher temperature than is possible where the exhaust outlets are located at a distance from the front of the upper passage, and this temperature of the radiating walls of the

combustion chamber will be substantially uniform throughout the entire extent of the combustion chamber, which is also impossible to be realized in a construction wherein the exhaust outlets are located at a considerable distance from the front or delivery end of the combustion chamber. The higher temperature which can be obtained with the combustion chamber shown herein over that which can be obtained with any other type or carborundum combustion chamber with which I am familiar, results in a much greater proportional increase in the efficiency of the installation in which such a chamber is used, as the heat transferred by radiation varies with the fourth power of the difference between the temperature of the heat-receiving surface (in this case the boiler) and the heat radiating surface.

In the boiler shown herein there are a plurality of series of tubes in the chamber above the combustion chambers, each series extending transversely of the furnace structure, the lowermost series being in close proximity to the tops of the combustion chambers and the other series being located above such lowermost series. The tubes in the lowermost series are heated practically entirely by radiation from the combustion chambers, substantially their entire length. The tubes in the series next above the lowermost series will be heated to some extent throughout the major portion of their length by radiation, though to a somewhat less extent than is the case with the tubes in the lowermost series. Because of the staggering of the tubes, the tubes in the third series will not be appreciably heated by radiation, but will be appreciably heated practically entirely by convection from the gases discharged from the combustion chamber while the tubes in the series further remote from the tops or roofs of the combustion chambers will be heated only by convection.

Also, because of the shortness of the baffle wall 4, there will be practically no heating of the lowermost series of tubes by convection except at the front ends thereof. This arrangement shields the tubes in the lowermost series from direct contact with the products of combustion, except at the front portions thereof; but, because the combustion is completed within each combustion chamber, the gases discharged from the combustion chamber are at a temperature which will not unduly heat the tubes through convection.

In order that the combustion chamber may radiate heat efficiently and produce the slagging of the ash, as hereinbefore described, it must be heated to a temperature of from about 1000° C. to 1400° C., which will render the said chamber incandescent; and this necessitates a combustion rate of at least 100,000 B. t. u.'s per cu. ft. per hour, which results in the transmission through the walls

of the combustion chamber and in the radiation from the outer surface thereof of at least 10,000 B. t. u.'s per square foot per hour. Operating at the temperatures mentioned 5 and at the rate of combustion specified, at least 40% of the heat resulting from the combustion will be transmitted by radiation to the boiler tubes.

Having thus described my invention, what 10 I claim is:—

1. A combustion chamber having a partition extending from its front wall toward and spaced from its rear wall and dividing said chamber into a lower and an upper combustion passage, the lower wall of said chamber and said partition being inclined downwardly from the front toward the rear thereof, and the said chamber having adjacent to the rear thereof, a delivery outlet communicating with the lower passage, means for sealing said outlet, means for supplying a mixture of pulverized fuel and air to the front of one of the combustion passages, the said combustion chamber being provided 25 with an exhaust outlet adjacent only to the front of the other combustion passage and the said combustion chamber also being composed principally of a refractory material having a thermal conductivity in excess of 30 0.006 cal/cm³/sec/°C.

2. A combustion chamber having a partition extending from its front wall toward and spaced from its rear wall and dividing said chamber into a lower and an upper combustion passage, the said combustion chamber and the said partition being inclined downwardly from the front to the rear thereof and the said chamber having adjacent the rear thereof a delivery outlet communicating 40 with the lower combustion passage, means for sealing said outlet, means for supplying a mixture of pulverized fuel and air to the front of the lower combustion passage, the upper combustion passage being provided 45 with an outlet near the front end only thereof, the said combustion chamber being composed principally of a refractory material having a thermal conductivity in excess of 0.006 cal/cm³/sec/°C.

3. A combustion chamber comprising a plurality of longitudinally extending sections each comprising side, bottom and top slabs, the front section having a front closure slab and the rear section having a rear 55 closure slab, the side slabs and the front slab being provided with seating portions, and a partition on such seating portions and extending toward, but spaced from, the rear slab, the said slabs and partitions being composed of a refractory material having a thermal conductivity in excess of 0.006 cal/cm³/sec/°C.

4. A combustion chamber comprising a plurality of longitudinally extending sections each comprising side, bottom and top 65

slabs, the front section having a front closure slab and the rear section having a rear closure slab, the side sections and the front section being provided each with an inwardly projecting ledge, a partition seated upon said ledges, the said ledges being arranged to support the partition in position to provide combustion passages extending from the front closure below said partition, around the rear end of the same, and above the said 75 partition, the upper passage having an outlet adjacent to the front only of said chamber, and means for supplying a combustible mixture to the front of the lower passage, the said combustion chamber and the said 80 partition being composed principally of a refractory material having a thermal conductivity in excess of 0.006 cal/cm³/sec/°C.

5. A combustion chamber for burning pulverized fuel, said chamber comprising a plurality of intermediate sections and a front and a rear section, a partition seated within 85 said sections and arranged to provide combustion passages extending from the front of the chamber alongside the said partition and around the rear of said partition, one of said passages having an outlet adjacent the front only thereof, and means for supplying a combustible mixture to the front of the passage which is not provided with such 90 outlet, the said combustion chamber and the said partition being composed of a refractory material having a thermal conductivity in excess of 0.006 cal/cm³/sec/°C. and the bottom of the said chamber being inclined downwardly from the front thereof and having a sealed outlet at the lower end thereof.

6. The combination, with a chamber, of a series of spaced combustion chambers within 100 said chamber, controllable means for supplying a combustible mixture to each of said chambers, the said chambers being placed side by side and each having upwardly convergent side walls providing upwardly flaring spaces between adjacent chambers and between the chambers at each side of the series and objects adjacent thereto, each of said chambers being composed principally of a refractory material having a thermal conductivity in excess of 0.006 cal/cm³/sec/°C. 110

7. The combination, with a water tube boiler, of a partition interposed between the front and back of said boiler and providing a vertical flue with such front, a partition or baffle interposed between the former partition and the rear of the boiler and extending downwardly from the top thereof, a combustion chamber arranged beneath the said boiler and having its top or roof substantially co-extensive in length therewith and immediately adjacent thereto, the said combustion chamber having intermediate the top and bottom thereof a partition extending from the front toward and spaced from the rear to provide upper and lower com- 120 125 130

bustion passages, the upper passage being provided near its front only with one or more outlets adapted to discharge into the first mentioned flue the rear end of the upper side of said passage being closed and the said chamber being composed principally of a refractory material having a thermal conductivity in excess of $0.006 \text{ cal/cm}^3/\text{sec}/^\circ\text{C}$. and means for supplying a combustible mixture to the front of said chamber and beneath said last mentioned partition.

8. The combination with a combustion chamber and a chamber thereabove, of a series of longitudinally extending tubes arranged within said second mentioned chamber, the roof of said combustion chamber forming a partition between said chambers and having one or more openings therein adjacent its forward end only, said series of tubes being arranged above and in close proximity to said roof so as to be heated by radiation therefrom, a second series of longitudinally extending tubes arranged above said first series, and means for causing the products of combustion to travel transversely of said tubes and to heat the same by convection, said combustion chamber being composed principally of a refractory material having a thermal conductivity in excess of $0.006 \text{ cal/cm}^3/\text{sec}/^\circ\text{C}$.

9. The combination, with vertically spaced series of longitudinally extending tubes, of a combustion chamber arranged below said tubes and having its top wall composed of a refractory material having a thermal conductivity in excess of $0.006 \text{ cal/cm}^3/\text{sec}/^\circ\text{C}$. and disposed below and adjacent to the lowermost series of tubes and serving to heat the lowermost tubes by radiation throughout substantially their entire length while protecting the same from direct contact with the products of combustion, said top wall having one or more openings in its forward end only, and means for directing the heated gases of combustion transversely of the tubes whereby to heat the same by convection.

10. A combustion chamber having a partition extending from its front wall toward and spaced from its rear wall and dividing said chamber into combustion passages arranged on opposite sides of said partition and communicating around the rear end of said partition, the said combustion chamber being inclined downwardly from one end to the other end thereof and having adjacent its lower end a delivery outlet, means for sealing said outlet, and means for supplying a mixture of pulverized fuel and air to the front of one of the said passages, the other passage being provided with an outlet adjacent the front thereof and one or more of the walls of said chamber being composed of a refractory material having a thermal conductivity in excess of $0.006 \text{ cal/cm}^3/\text{sec}/^\circ\text{C}$.

11. The combination, with a boiler, of a combustion chamber having a wall composed

principally of a refractory material having a thermal conductivity in excess of $0.006 \text{ cal/cm}^3/\text{sec}/^\circ\text{C}$. arranged in close proximity to said boiler whereby the boiler is in position to absorb radiant heat efficiently from such wall, and means for burning fuel in said combustion chamber thereby to heat the said wall to a degree to cause it to transmit heat rapidly and efficiently by radiation to said boiler, said combustion chamber having a plurality of passages, serially arranged, and provided with an exhaust outlet adjacent one end only thereof for delivering the gases resulting from combustion in operative relation to the boiler whereby the boiler is heated also by convection from such exhaust gases.

12. The combination, with a boiler, of a combustion chamber having its upper wall in close proximity to said boiler, the said combustion chamber having an inclined bottom provided at its lower end with an outlet for the discharge of molten ash, means for sealing said outlet, means for introducing pulverized fuel into said chamber, the upper wall of said chamber extending substantially the full length of said chamber and being composed principally of a refractory material having a thermal conductivity in excess of $0.006 \text{ cal/cm}^3/\text{sec}/^\circ\text{C}$. thereby to heat the said boiler efficiently by radiation from such wall and the combustion chamber being also provided with a discharge outlet for the gaseous products of combustion located adjacent one end only thereof, the boiler being provided with means for causing said gases to flow over the surface thereof whereby the boiler will be heated by convection from said gases as well as by radiation from the upper wall of the combustion chamber.

13. The combination, with a heat absorber, of a combustion chamber having a wall thereof arranged in close proximity to said heat absorber and composed principally of a refractory material having a thermal conductivity in excess of $0.006 \text{ cal/cm}^3/\text{sec}/^\circ\text{C}$. said chamber being provided with a discharge outlet for products of combustion located adjacent to one end only thereof, whereby the said wall may be heated uniformly throughout its entire extent and efficient combustion may be secured within said chamber, the said combustion chamber comprising a plurality of serially related passages.

14. The combination, with a liquid container, of a combustion chamber having a wall extending substantially the full length thereof and arranged in close proximity to said liquid container, said wall being composed principally of a refractory material having a thermal conductivity in excess of $0.006 \text{ cal/cm}^3/\text{sec}/^\circ\text{C}$. and said chamber being provided with an outlet adjacent one end only thereof adapted to deliver products of combustion to contact with said liquid container, the said combustion chamber having its bot-

tom inclined downwardly and provided at its lower end with an outlet leading to the atmosphere and means for sealing the same, and means for introducing pulverized fuel into said chamber.

15. A combustion chamber having a partition extending from its front wall toward and spaced from its rear wall and dividing said chamber into combustion passages arranged on opposite sides of said partition and communicating around the rear end of said partition, the said combustion chamber being inclined downwardly from one end to the other end thereof and having adjacent its lower end a delivery outlet, means for sealing said outlet, and means for supplying a mixture of pulverized fuel and air to the front of one of the said passages, the other passage being provided with an outlet adjacent the front

thereof and one or more of the walls of said chamber being composed principally of silicon carbide.

16. The combination, with a heat absorber, of a combustion chamber having a wall thereof arranged in close proximity to said heat absorber and composed principally of silicon carbide, said chamber being provided with a discharge outlet for products of combustion located adjacent to one end only thereof, whereby the said wall may be heated uniformly throughout its entire extent and efficient combustion may be secured within said chamber, the said combustion chamber comprising a plurality of serially related passage ways.

In testimony whereof, I hereunto affix my signature.

HIRAM B. CANNON.
